UNITED STATES PATENT OFFICE.

WILLIAM W. ANDERSON, OF TAUNTON, MASSACHUSETTS, ASSIGNOR OF ONE-HALF TO LOUIS BÜSIEIRE, OF TAUNTON, MASSACHUSETTS.

WET-WASH DRIER FOR LAUNDRIES.

No. 918,114.

Specification of Letters Patent.

Patented April 13, 1909.

Application filed April 6, 1908. Serial No. 425,324.

To all whom it may concern:

Be it known that I, WILLIAM W. ANDERSON, a citizen of the United States of America, and a resident of Taunton, in the county 5 of Bristol and State of Massachusetts, have invented certain new and useful Improvements in Wet-Wash Driers for Laundries, of which the following is a specification.

My invention relates to improvements in 10 drying-machines, such for example as are employed in laundries for drying moisture from clothes after they have been washed or cleansed and subjected to the action of hydro-extractors, and it consists in certain 15 novel features of construction, arrangement and manner of operation, all as more fully hereinafter set forth and claimed.

The object I have in view is to produce a 20 machine, or "wet - wash" drier, having a much greater degree of efficiency than is possessed by other driers of this type heretofore devised.

My improved drying-machine is simple in 25 construction; comparatively inexpensive to manufacture; economical in its operation; not liable to get out of order; it is adapted to be readily and quickly charged with one or more independent washings or "batches", and also as readily adaptable to discharge 30 them therefrom after being subjected to the drying process, the several washes meanwhile being kept separated from one another while the machine is in action, and then discharged into trucks or analogous receptacles 35 having correspondingly separated compartments.

In a machine embodying my improvements the attendant is enabled to perform his work with greater facility and rapidity 40 and with much less discomfort and inconvenience owing to the fact that while thus performing the necessary manipulations or duties incident to the drying process he is not directly exposed to the comparatively high 45 degree of heat employed in the machine.

In the accompanying two sheets of drawings, Figure 1 represents a side elevation, in 50 partial section, of a drying-machine embodying my improvements, the parts or elements of the machine being in the normal operative positions. Fig. 2 is a corresponding front end elevation, also in partial section. Fig. 3 is a partial cross-sectional view (in enlarged scale) taken substantially on

line $z-z$ of Fig. 1. In this view, however, the two doors are open, corresponding with the charging position. Fig. 4 is a similar cross-sectional view showing the drum or cylinder held in position, as in discharging the dried wash from the drum. Fig. 5 is a partial 60 front end elevation, partly broken away, showing the relation of the parts corresponding with the position shown in Fig. 4. Fig. 6 is a partial side view corresponding with Fig. 5, a portion being broken away. Fig. 7 65 is a transverse sectional view taken on line 7-7 of Fig. 6. Fig. 8 is a direct side elevation, viewed from arrow 8 of Fig. 7, some of the parts being omitted, and Fig. 9 is a horizontal sectional view taken on line $x-x$ of 70 Fig. 7.

In the drawings the revoluble steam-heated cylinder or drum A is provided with hollow trunnions mounted in bearings supported in the ends of the casing or housing B. The cylinder is completely inclosed within the casing chamber and surrounded by an ample space for the circulation of heated air. A suitable charging opening d^2 is formed in one side of the casing, a swinging door d serving 80 to keep the opening normally closed or protected. In order to prevent to some extent the escape of heated air from the casing chamber and also to protect the attendant while the door d is temporarily open, as for example when charging the cylinder with the wet-wash or material to be subjected to the drying process, the narrow longitudinally extending auxiliary door or partition b may be employed; this device when swung into the 85 operative position, indicated in Fig. 3, then practically closing the space lying between the cylinder and casing at that point.

As drawn each end of the casing has a central opening therethrough located below 95 the drum to freely receive a truck or receptacle p having an open top. Each receptacle has an outer flange adapted when properly positioned under the cylinder to completely close the opening and thus prevent the escape of hot air from the casing chamber at that point. The rear end of the casing has two inlet-pipes or nozzles w adapted to be connected to a blower for forcing air into the casing chamber. In order to increase the 100 temperature of said air oppositely disposed auxiliary heaters or steam-heating coils D may be located in the space lying between 105

the said members p and the corresponding side of the casing. The inlet end a^1 of each coil is adapted to connect with a suitable steam supply; the exhaust passing out at a^2 , 5 near the front end of the machine. See Figs. 1. and 2. The said air after circulating throughout the chamber and cylinder becomes more or less charged with moisture and escapes in the form of vapor via the outlet b^4 at the top of the machine. In order to 10 form a chute or incline for insuring the proper delivery of the dried wash from the cylinder into the said receptacles p and also to provide means for more effectually diffusing 15 or distributing the heated air throughout the casing chamber I employ oppositely located beveled perforated partitions or fixed screens e . These extend longitudinally of the machine and are disposed above said coils D 20 and lie contiguous to the drying cylinder A . See Figs. 2 and 4.

The revoluble steam-heated cylinder A is provided with two hollow annular heads or end members a united together longitudinally of the machine by a series of suitably spaced peripherally arranged parallel tubes t , the ends thereof being secured to and in continuous open communication with the respective heads or hollow rings a . These 30 tubes constitute the walls or barrel proper of the cylinder and as drawn are secured in the inner sides of the members a . The hub of each trunnion is hollow, as before stated, and carries radiating arms or spokes a^4 , the outer 35 ends of the latter being secured to the sides of the respective members a . Steam is conducted from a boiler or other suitable source into the inlet-pipe i , its lower end being centrally inserted and packed in the front trunnion in a well-known manner. When in use 40 the steam passes freely and directly from the trunnion into the front head a via the connecting pipes i' , Fig. 1, and after circulating through it and through the tubes t it, as well 45 as the water of condensation, passes into the back head and its pipe connections i^2 into the rear trunnion and escapes via outlet-pipe i^3 . The ends of the cylinder are protected or 50 closed by means of sheet metal disks or screens u^4 so as to keep the wash or material being treated from escaping from the end compartments. The screen may be secured to said arms a^4 . See Fig. 9.

The interior of the cylinder may be divided 55 transversely into a plurality of compartments by suitable partitions. In the last-named figure a portion of a central partition is indicated sectionally at u . As thus arranged two compartments are produced in 60 the cylinder.

The interior of the cylinder is rendered 65 readily accessible through a suitable opening d^4 , produced by leaving out a number of the tubes t , as clearly represented. This opening is kept normally closed or protected

by the freely slideable door c movable circumferentially in the two curved end grooves c^1 . The door has a pair of handles or grips c^2 for obvious purposes and located near its lower edge. The door is provided at or near each 70 end thereof with a lug or ear l in which a horizontally disposed bolt r is slidably mounted. Said bolt has a comparatively short endwise movement and having its outer end r^1 arranged to enter a recess r^2 75 formed in the adjacent side of the head a . Each bolt is resisted by a light spring v , Fig. 9, and is attached to a chain or flexible connection h , in turn attached to a vertically slideable block g supported in ways f located 80 at the center of the door. As thus constructed and arranged the two bolts of the closed door are adapted to be simultaneously withdrawn or unlocked from the heads a whenever the block g is moved upwardly 85 from its normal position a proper distance; the guides h^1 insure a direct endwise pull upon the bolts. A collar r^3 (Figs. 8 and 9) constitutes a stop for limiting the rearward movement of the bolt. It may be added 90 that all the said members of the locking device are mounted on the door c and rotate bodily and in unison with the cylinder. I prefer to place the said handles c^2 below or in advance of the two alining bolts r with 95 respect to the direction of rotation.

The cylinder remains stationary while it is being charged and discharged. Fig. 3 represents it in the first-named position, the doors d and c then being open, and Figs. 4, 7, 8 and 9 show the discharging position of the cylinder. In this position the opening d^3 is at 100 the bottom and uncovered, the casing door then being closed.

The following is a description of the means 105 for mechanically unlocking and opening the door c : A rock-shaft s is mounted at the left in the ends of the casing B and extends longitudinally thereof below the screen e . To the shaft is secured a central lever m^1 adapted in use to contact with the underside of said block g , and also two levers m arranged to engage the handles c^2 of the door. As drawn one end of the shaft extends outwardly through the front end of the casing 110 and has secured thereto an operating lever s^1 and quadrant member s^3 ; the latter supporting a weight s^4 . If desired stops or adjusting screws s^2 may be employed for limiting the angular movement of the shaft and 115 its levers. See Fig. 5. The levers m^1 and m are positioned with respect to one another and to the members g and c^2 so that upon swinging the working lever s^1 from the normal or dotted line position, Fig. 5, the slowly 120 revolving cylinder will first cause the block g of the door c to engage the free end of the positioned lever m^1 , thus arresting the slideable block in the guides f and withdrawing the spring-pressed bolts r from the respective 125 130

heads *a*; at substantially the same instant the positioned levers *m* contact with the handles *c*² of the door to hold the latter stationary, the cylinder continuing its movement until the opening *d*³ is fully uncovered (Fig. 7), followed by stopping the machine.

If desired an arm or swinging shoe *b*² may be employed as a brake upon forcing it against the periphery of the front head of 10 the cylinder. The brake action is controlled by a hand-wheel *b*³ secured to a suitably mounted screw bearing against the shoe. See Figs. 5 and 6.

In my improved drying-machine the 15 washed clothes are preferably taken say from a hydro-extractor while in a wet or moist state and placed in a compartment of the then open stationary cylinder A (Fig. 3), followed by swinging the member *b* outwardly 20 and closing the doors *c* and *d* (the levers *s*¹, *m* and *m*² then being in the lower or normal position, indicated by dotted lines in Figs. 5 and 7) and starting the cylinder in motion.

The driving means as drawn consists of suitable belt-driven pulleys and gearing arranged in any well-known way. See Figs. 1 and 2. The action of the slowly revolving steam-heated cylinder in co-operation with air from the nozzles *w*, heating-coils *D* and 30 screens *e* produce a circulation of the heated air throughout the casing chamber and through the interstices or continuously open narrow spaces formed between the tubes *t* or wall of the cylinder. The moisture thus 35 evaporated from the wash mingles with and charges the air and passes from the casing chamber via outlet *b*⁴ in the form of vapor; the result being to produce a more rapid, thorough and uniform drying of the wash or

40 material confined in the cylinder. This operation is succeeded by swinging the said levers upwardly to the full line position so as to lie in the path of the members *g* and *c*² of the then moving door *c*; the conjoint action causing 45 the bolts *r* to be withdrawn and the door to then remain temporarily stationary, the cylinder at the same time continues its own movement until the opening *d*³ is fully uncovered and then stopped; the wash may

50 now fall therethrough by gravity into the receiver *p* positioned below it. Prior to restarting the open cylinder the said levers are returned to the normal position, followed by turning it to and stopping it at the charging 55 point, the casing door *d* meanwhile being opened and the partition *b* swung into place, see Fig. 3. After introducing the wet-wash into the cylinder and returning member *b* to the normal position the door *c* is moved down- 60 wardly to its limit to close the opening *d*³, the bolts *r* at the same time springing into the registering bolt-holes *r*², thereby locking the door, followed by closing the casing opening *d*² by means of the outer door *d*. The thus 65 closed positions are indicated by dotted lines

in Fig. 3. The machine is next set in operation and the moisture evaporated from the wash as before described.

It may be added that changes of modifications in the construction of the machine may 70 be made without departing from the spirit of the invention.

I claim as my invention and desire to secure by United States Letters Patent:—

1. In a drier of the character described, a 75 revolvably mounted cylinder or drum comprising hollow ends or heads, a series of suitably spaced peripherally arranged tubes disposed between in open communication with and connecting said heads and constituting 80 the barrel proper of the cylinder, a charging opening formed in said barrel part, a door for normally closing said opening, means for rotating the cylinder, and means for introducing steam into said heads and tubes and 85 discharging it therefrom.

2. In a drier of the character described, a revolvably mounted steam drying cylinder having intercommunicating hollow heads and barrel, an opening extending through 90 the barrel through which the cylinder is adapted to be charged with the wet wash or material to be dried, a door normally closing said opening and being revoluble with the cylinder, means for locking and unlocking 95 the door, one or more transverse partitions disposed in the cylinder for dividing it into a plurality of independent compartments, means for circulating steam in the heads and barrel of the cylinder for evaporating moisture from the material contained in said compartments, and means for rotating the cylinder. 100

3. In a drier of the character described, the combination with a revoluble moisture evaporating cylinder having openings through 105 its barrel part for the circulation of air and also provided with a door-covered charging opening, of a stationary casing freely surrounding or enveloping the cylinder having 110 a door-covered charging opening arranged to register with that of said cylinder, means for introducing air into the drier and circulating it therein, oppositely disposed heating coils extending longitudinally of the machine and located within and near the base thereof, diaphragms positioned above said coils for deflecting heated air direct into the cylinder to facilitate the drying operation, a normally stationary pan removably mounted under the cylinder to receive therein the clothes or wash direct from the cylinder at the completion of the drying process, and a discharge outlet from the casing for the escape of vapor or moisture-laden air. 115

4. In a drier of the character described, the combination of a revoluble cylinder having the walls of its barrel portion hollow and arranged for the circulation therein of steam, suitable apertures extending through 120

said walls for the circulation of heated air, a stationary casing or housing freely enveloping the cylinder, independent door-protected openings formed in the casing and cylinder arranged to register with each other when the cylinder is being charged with the wet wash or material, means for uncovering and closing said openings, and a bottom pan or truck member removably positioned in the casing chamber so as to receive the dried wash direct from the cylinder.

5. In a drier of the character described, the combination of a revolute cylinder divided interiorly into a plurality of compartments and having its barrel portion provided with a hollow wall for the circulation of steam, a door protected aperture in said wall through which the wet-washes are introduced into the respective compartments of the cylinder and discharged therefrom, a housing inclosing the cylinder, a pan or truck provided with compartments registering with those of the cylinder removably positioned in the housing chamber, and means for opening said aperture in the cylinder to permit the then dried washes to fall therefrom into the respective compartments of the said pan member.

6. The combination with a suitably mounted revolute drying cylinder having a charging opening formed in its wall, a door normally closing said opening provided with a locking device, and means for rotating the cylinder, of a housing inclosing the cylinder,

means operatively connected with said locking device arranged whereby the latter is released, the door arrested in its rotating movement and the said opening in the cylinder uncovered before the latter is brought to a state of rest, means operable for closing said door after the cylinder has been rotated to the charging position, means for introducing air into the drier and circulating it therein, oppositely disposed heating coils extending longitudinally of the machine and located within and near the base thereof, and diaphragms positioned above said coils for deflecting heated air direct into the cylinder to facilitate the drying operation.

7. In a drier of the character described, the combination of a revolute drying cylinder having its barrel provided with a peripheral door-covered charging opening; a stationary casing surrounding a portion of the cylinder and forming an air space therebetween also provided with a door-covered opening disposed so as to register with that of the cylinder, and means for temporarily closing a portion of said air space contiguous to said openings while the latter are uncovered during the charging of the cylinder.

Signed at Providence, R. I., this 4th day of April, 1908.

WILLIAM W. ANDERSON.
